(57) **CLAIM**

The ornamental design for a motorcycle frame neck cover, as shown and described.

DESCRIPTION

FIG. 1 is a front perspective view of the motorcycle frame neck cover of the present invention for a right side of a motorcycle frame neck.

FIG. 2 is a front view thereof; and,

FIG. 3 is a rear view thereof.

Those portions of the motorcycle frame neck cover shown in broken lines form no part of the claimed design.

The broken lines on the rear surface indicate that the rear surface forms no part of the claimed design.
